REPRODUCING APPARATUS

Gene Leofanti, Dongan Hills, N. Y.

Application May 10, 1934, Serial No. 724,959

7 Claims. (Cl. 33—24)

This invention relates to reproducing apparatus. More particularly, it relates to a machine for enlarging or reducing statues and forms and for reproducing such statues or forms for making mirror images of such statues or forms without requiring a double reproduction of such statues or forms.

It is among the objects of this invention to provide a simply operable apparatus for enlarging or reducing forms, whether of wood, stone, plaster, marble, clay and the like, to provide efficient apparatus for reproducing the same or opposite sides of a form from a model in one operation without necessitating the formation of an additional model from which to work.

One further object of this invention is to provide apparatus whereby a model and a form to be made therefrom may be moved or rotated in unison in one direction or in relative clockwise direction.

In the drawings:

Fig. 1 is a front elevation of a preferred form of my embodiment;

Fig. 2 is a top plan view of the machine;

Fig. 3 is a view taken on line 3—3 of Fig. 1, and looking in the direction of the arrows;

Fig. 4 is a detail view taken on line 4—4 of Fig. 1;

Fig. 5 is a detail taken on line 5—5 of Fig. 1; and

Fig. 6 is a diagrammatic illustration of the means for making (reproducing) mirror images of a form or statutory.

Referring to the drawings, in which similar reference characters indicate like parts throughout, the preferred embodiment has a base 10 which can be mounted on any suitable support, not shown. Said base has its front partly cut away, as seen in Fig. 1, and hollowed, as shown in Figs. 4 and 5. It also has at its top portion a plurality of spaced, horizontal rails, 11, 12, 13 and 14, lying in the same level or horizontal plane. The rails extend preferably the length of the base and extend upwardly from the surface of the base, forming triangulate ridges, and providing recesses or grooves between them for accommodating base plates 15 and 16. Each of said plates has a plurality of spaced grooves, 17, 18, 19 and 20, on its under face for rails 11, 12, 13 and 14, respectively, to permit sliding of the base plates along the base. It is to be noted that the plates are slightly elevated from the base and that there is no crosswise shifting of the plates, thereby avoiding any unevenness in the reproduced form when made.

Base plates 15 and 16 are retained firmly on rails 11, 12, 13 and 14, by means of a pair of sliding plates 21, bolt 22 passing through the plates 21, and each of the base plates, and a nut 23 for retaining the plates 21 which abut the lower faces of rails 12 and 13. The straight rails, as shown, permit a linear movement of the plates without encountering any lateral resistance to such movement, as in cases where the plates are in direct contact with a base. The base plates are each provided with a circular groove 24 for retaining therein ball bearings 25 which also fit in circular groove 26 of turntables 27 and 28. The turntables have a hub 29 for a connecting rod 30 passing through an integral central tubular extension piece 31 at one end of which rod is a bevel gear 32.

Mounted on turntables 27 is a pedestal 33 for a model form or other type of statutory which is to be reproduced. Said pedestal may be of any desired height, depending upon the size of the reproduction. Turntable 28, however, is of relatively larger diameter than turnplates 27 to accommodate a large block from which a form is made, corresponding with that of the model on pedestal 33. It will be noted that the turntables are on a common level or plane with the form or reproduced pieces thereon, and do not shift laterally or forwardly and backwardly, thereby avoiding any defective reproduction.

In order to get an exact relative position and to move carriages 15 and 16 along rails 11, 12, 13 and 14 of base 10, a worm or screw rod 34 is provided, which is connected with depending clamping members 35. Said members have a threaded opening for the worm rod and permit the carriages to move in unison in one direction. The relative distance between the carriages may be varied by the operator, by first disconnecting carriage 15 from worm rod 34 by continually turning the rod and then turning the rod by means of handle wheel 36 so that the same is unscrewed from depending member 35 of carriage 16. Carriage 15 is then connected with the worm rod and ready for further use. I may also adjust and regulate the relative distance between the carriages by using clamping members 35 having vise like jaws, not shown, which may be loosened at any interval on the worm rod to permit spacing carriages.

Turntables 27 and 28 may be rotated in unison either in the same or opposite directions. To permit rotation in the same direction, bevel gear 32 of each of turntables 27 and 28 is in

respective connection with bevels 37 and 38, by being keyed to a shaft 39. A plurality of supports 40 extending into the recessed portion of base 10 permit easy rotation of shaft 39 by means of a handle wheel 41. If the turntables are to be rotated in opposite directions, bevel gear 42 keyed to shaft 39, is provided for connection with gear 32 of turntable 27, in which case, gear 37 is disconnected. This feature is advantageous since the model and type to be reproduced will turn toward each other, thereby forming a statue directly from the original in one operation instead of in two, as heretofore required.

15 The side top of the base 10 is provided with a scale 38' along one of its edges as shown in Fig. 2, to permit spacing of the sliding plates 15 and 16.

20 On rails 12 and 13 of base 10 is a carriage 43 for a hollow slideable post 44 which can be fixed in position on the base by means of engaging a bolt 45 depending from the post and through a slide plate 46 with a nut 47. Post 44 is provided with a telescopic member 48 provided with a ball end 49 for supporting a socket 50 of main arm or compass beam 51. Said telescopic member may be raised or lowered in post 44 and retained in any fixed position by means of a set screw 52. Beam 51 is movable on ball end 49 in any direction and is joined therewith preferably at one end in order to permit easy movement during the reproducing operation.

25 Adjacent hollow slideable post 44 is another slideable hollow post 53 in engagement with a carriage 54 and held in position against base 10 by means of members 55, 56 and 57. The interior of the post is corrugated for an equalizing rod 58 containing at one end a transverse opening 59 for opposed ball bearings 60, which are adapted to form a frictional engagement with corrugations 61, by means of tensioned spring 62. By this arrangement, the rod remains in the position in which it is left in order to facilitate handling of compass beam 51. The upper end of rod 58 has a saddle 63 for a knuckle 64 of a linkage member 65. The other end of member 65 also has a knuckle 66 fitting into a socket 67 of a collar 68, thereby forming a 30 universal joint.

50 Collar 68 has an interior circumferential groove for ball bearings 69 for holding compass beam 51 in engagement. Said beam is also grooved in order to accommodate said ball bearings and can be easily rotated clockwise or counter-clockwise around the collar, moved on ball end 49 as a pivot at an incline or decline or at an angle on its horizontal. It is to be noted that the beam has adjustable counter weights 20 at one end to facilitate handling of the same. Furthermore, saddle 63, knuckles 64 and 66, and socket 67, form a universal joint thereby allowing for freedom of movement of compass beam 51.

55 The compass beam is provided along its length with straight edged scalar dimensions preferably in feet and inches, corresponding with scale 38' on base 10, for setting apart at any indicated 60 position, brackets 71 and 72 provided with an index 73. The brackets have a circular groove 74 for ball bearings 75 to permit rotary movement of a plate casting 76 which has a depending member 77 for accommodating adjustably 65 mounted tools 78 and 79. Ball bearings 75 are

retained in position between the brackets 72, 73, and plate casting 76, by means of screw bolt 80 and nut 81.

70 Brackets 71 are provided with tightening means 82 and a set screw 83 which fits in a groove 84 on the beam. Said groove 84 acts as a guide for brackets 71 and 72 to maintain them on the same level. This arrangement eliminates all unnecessary level adjustments on the brackets.

75 The tail ends of plate castings 76 are provided with an opening for a bushing 85 to accommodate a set pin 86.

80 In order to move the tools 78 and 79 on the plate castings, a handle rod 87 is provided with a plurality of openings therein for pins 86. The rod is retained between the bushings 85 and the set pins 86 and is adapted to be rotated about the center of the beam 51 as its axis. Furthermore, tools 78 can be rotated about screw bolts 80 as their pivotal axes by pushing, raising or lowering the rod. Furthermore, said handle rod can be arranged on corresponding tail ends of the plate castings, as shown in Fig. 2, whereby the tools will move in unison and parallel to each other during a reproducing or cutting operation. If the rod is connected to the diagonally opposite tail ends of the plate castings, as shown schematically in Fig. 6, the tools move so that a line extended from them would intersect each other. Furthermore, the diagonally opposite connection of the rod with the plate castings permits enlarging or reduction of the side of the object directly opposed to the model, when the turntables are rotated in relative counter-clockwise directions. In other words, by this arrangement, mirror images of the form are obtained in one operation.

85 From the foregoing description taken in connection with the accompanying drawings, it is to be noted that an even and uniform motion is imparted to the turntables which are arranged in a common level or plane. Furthermore, the turntables may be moved along said plane or level at any desired interval without requiring any tedious adjustments, and rotated in unison or counter to each other. Also, the cutting or working tools are adjustable to any angle for working in two dimensions thereby permitting easy enlarging, reducing or reproduction of 90 forms. The tools are mounted on an easily balanced beam which moves about a pivot and which can be easily counterbalanced or moved about in a gyrating or swinging manner.

95 The essential features of the invention include a level base, a plurality of adjustably slideable and rotatable turntables and an easily operable pantograph device which is rotatable on its horizontal axis and can be raised, lowered or swung about a pivot. Furthermore, said pantograph device is counter balanced and permits working of tools in a parallel plane or at intersecting planes.

100 While several important features of a preferred embodiment of the invention have been described, it is to be understood that several changes or modifications as to forms, use of material, arrangement of parts may be made without departing from the spirit and scope of the invention.

I claim:

1. Apparatus for enlarging, reducing or reproducing statutory and like form, including a base with a plurality of equi-spaced tracks extending longitudinally along its top, a pair of turntables, 105

slidable on the base along said tracks and operably movable longitudinally and circularly in unison thereon, means in the base in connection with said turntables for operating same, an extensible standard post mounted on a pair of said rails slidable along the longitudinal axis of the base, clamping means for engaging the post to the tracks and the base, a pantograph beam disposed perpendicular to and pivotally mounted on said post, a plurality of horizontally movable, coacting scribing tools in operable connection with the beam and with each other for working on the form and block on the respective turntables, and balancing means in connection with the base and one end portion of the beam for retaining the beam in position during the operating movements of the scribing tools.

2. Apparatus for making forms comprising a longitudinally hollowed base, a plurality of movable turntables arranged on the same level for retaining a model and block thereon respectively, means for sliding said tables along said base in unison, means in the hollow portion of the base in connection with the turntables for rotating the same uniformly and in unison, a standard post extending upwardly from the base, a beam pivoted to said post and extending across the top of the base at a distance therefrom, means in connection with the beam for following the outline of the model on one of the turntables, and cutting means also in connection with the beam for cutting the block on the other turntable so as to correspond in outline with the model on said first turntable.

3. In apparatus for producing a form from a model, the combination with a centrally hollowed base having a plurality of equi-spaced longitudinal tracks lying in the same horizontal plane thereon, of a pair of carriages slidable in unison on said tracks on the base, a turntable for each of said carriages, means depending from each turntable extending into the hollow of the base, means mounted on the base in connection with said first means for rotating said tables, a slidable standard post mounted on said base having a telescopic adjustable extension thereon, a beam weighted at one end and pivotally mounted adjacent said end to the extension, another slidably adjustable post mounted on said base, adjacent the first post, having a universal joint in connection with the beam for fixing the movement of the same, and a pair of operable scribing tools lying in the same horizontal plane with respect to the pivotal connection between the beam and the telescopic adjustable post, rotatably engaged to said beam and in connection with each other, one of said tools being used for following the outline of the model on one of the tables and the other tool being used for cutting the form on a block on the other table.

4. In apparatus for reducing, enlarging or reproducing forms, a base with a plurality of equi-spaced tracks extending longitudinally on its top and arranged in a common level plane, a plurality of carriages slidable horizontally on said tracks to permit straight line movement of the carriages thereof, means in connection with said carriages for moving the same in unison along the table, a turntable in substantially frictionless engagement with each of said carriages for holding a model or form thereon, means extending through the base for rotating said turntables on their carriages in mutually opposite circular directions, a standard post slidable on a pair of said tracks, a telescopic member slid-

able in and out of the said post, a cross beam pivotally mounted on said telescopic member and extending above the tops of the turntables, a pair of collars slidable along said beam, and a plurality of means in connection with the collars of said beam and in operable connection with each other for working on the model and block on the respective turntables.

5. In apparatus for making statuary and the like, a longitudinally hollow base having a plurality of equi-spaced longitudinal tracks on its top, a pair of carriages slidable in unison to any desired relative distance on said tracks, means extending the length of the hollow portion of the base in connection with the carriages for moving the same in unison on the tracks, a turntable mounted on each carriage, ballbearing means intermediate the carriages and turntables for permitting easy rotation of the carriages, means depending from the center of the carriages into the hollow portion of the base, means extending through the base in connection with the depending means of each turntable for rotating the same in unison, one of said tables having a pedestal thereon for accommodating a model, and the other table being adapted to accommodate a block, a pair of adjacent slidable standard posts on a plurality of the tracks, a compass beam pivotally mounted at one end to one of the posts and in rotatable engagement with the other post, and a plurality of scribing tools pivotally connected with the beam for the form and block on the respective turntables.

6. In apparatus for reproducing, making, enlarging or reducing statuary and the like, the combination of a longitudinally hollowed base having a scale thereon, and a plurality of equi-spaced longitudinal tracks on its top, lying in the same plane, one pair of said tracks lying adjacent the long edges of the base and the other pair lying adjacent the long edges of the intermediate hollow portion of the base, a pair of carriages slidable on said tracks, means extending through the hollowed base and in connection with the carriages for moving said carriages in unison along the tracks, a turntable on each carriage for a form or block thereon, frictionless ball bearings intermediate each carriage and turntable, means in the base for revolving the tables in unison on their carriages, a compass beam above the turntables having a scale thereon, intermediate slidable means on the inner pair of the tracks on the base pivotally supporting the beam adjacent one of its ends, a pair of collars adjustably mounted along said beam, a scribing compass tool horizontally rotatable about the base of each of said collars adjustable to correspond with dimensions on the scale of the base, interconnecting linkage means for the tools for moving the same in unison, said tools being spaced on said beam to correspond with the spaced centers of the carriages, and means adjacent said slidable means in connection with the base for fixing the elevational movement of the beam about said slidable means as a pivot.

7. Apparatus for making forms of various shapes and outline, comprising a base having a longitudinally hollowed central portion, a plurality of equi-spaced tracks extending longitudinally along the top of said base, one pair being adjacent the edges of the top and one other pair being adjacent the edges of the hollowed portion, a pair of carriages slidable along said tracks, a turntable for each of said car-

riages, means intermediate the carriages and the turntables permitting relatively frictionless movement of the turntable with respect to the carriage, depending clamp means on each carriage extending into the hollow portion of the base, rotatable screw means interconnecting the clamp means for sliding the carriages in their

tracks in unison, means in connection with the turntables for rotating the same in same or opposite directions, a telescopically adjustable post slidably mounted on the inner pair of said tracks, and pantographic means in pivotal connection with the post for marking on said forms. 5

GENE LEOFANTI.
